COMBINED DISPLAY RACK AND MERCHANDISE HOLDERS

Tony J. Bressickello, 13015 S. Normandi Blvd.,
Gardena, Calif. 90249

Filed Mar. 4, 1975, Ser. No. 555,178

Term of patent 14 years

Int. Cl. D6—04; D20—02

U.S. Cl. D6—188

FIG.1

FIG.3

FIG. 1 is a perspective view of a combined display rack and merchandise holders showing my new design;

FIG. 2 is a side elevational view thereof; and

FIG. 3 is a front elevational view thereof.

I claim:

The ornamental design for a combined display rack and merchandise holders, substantially as shown.
